United States Patent Office

Des. 191,645
Patented Oct. 24, 1961

191,645

CAKE OF SOAP OR THE LIKE

Charles T. Gerhart, Cincinnati, Ohio, assignor to The Procter & Gamble Company, Cincinnati, Ohio, a corporation of Ohio

Filed Nov. 12, 1959, Ser. No. 58,321

Term of patent 14 years

(Cl. D73—1)

FIG. 1.

FIG. 4.

FIG. 2.

FIG. 3.

FIG. 5.

I claim:

The ornamental design for a cake of soap or the like, as shown.
